UNITED STATES PATENT OFFICE

HAROLD D. REICHARD, OF NEWARK, OHIO, ASSIGNOR TO BARNSDALL CORPORATION,
OF TULSA, OKLAHOMA, A CORPORATION OF DELAWARE

DESIGN FOR A TIRE

Application filed June 3, 1931. Serial No. 40,068. Term of patent 7 years.

To all whom it may concern:

Be it known that I, HAROLD D. REICHARD, a citizen of the United States, residing at Newark, in the county of Licking and State of Ohio, have invented a new, original, and ornamental Design for Tire, of which the following is a specification, reference being had to the accompanying drawings, forming a part thereof.

Figure 1 is a perspective view of a tire tread showing my new design,

Figure 2 is a plan, on an enlarged scale, of a portion of the tire tread showing the design of Figure 1,

Figure 3 is a cross section on the line 3—3 of Figure 2.

I claim:

The ornamental design for a tire, as shown.

HAROLD D. REICHARD.
